UNITED STATES PATENT OFFICE.

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY.

FLUID-PRESSURE TOOL.

Application filed June 3, 1923. Serial No. 644,097.

This invention relates to fluid pressure operated tools having a piston reciprocated by fluid pressure and is more particularly concerned with the mechanism for controlling the operation of the piston, such as the valve and associated parts which determine the cycle of operation of the tool and its efficiency and durability in service. Among the objects of the invention are to reduce wear of parts, to promote smoothness and accuracy of valve operation, to eliminate all tendency of the valve to flutter, and in general to improve the construction of previous devices in the interest of more satisfactory service.

In order to facilitate the explanation of the novel features, the invention is illustrated as embodied in a chipping hammer, but it is to be understood that the invention is not limited to the specific form, arrangement or operation of parts herein shown and described but is adapted to such other uses, combinations and structural modifications as fall within the scope of the appended claims.

In the drawings Figure 1 is a longitudinal sectional view through a chipping hammer embodying the features of the invention substantially on the line 1—1 of Fig. 5 and showing the piston at the beginning of its return stroke;

Figure 2 is a view similar to Fig. 1, but taken at a different angle as indicated by line 2—2 of Fig. 5, and showing the piston on its forward or working stroke;

Figure 3 is a fragmentary longitudinal sectional view substantially on the line 3—3 of Fig. 5 showing the valve in elevation, the parts being in the position shown in Fig. 1;

Figure 4 is a transverse sectional view on the line 4—4 of Fig. 1;

Figure 5 is a transverse sectional view on the line 5—5 of Fig. 1;

Figure 6 is a transverse sectional view on the line 6—6 of Fig. 1;

Figure 7 is a transverse sectional view on the line 7—7 of Fig. 2;

Figure 8 discloses in perspective the valve lid, the valve case and the adjacent end of the hammer cylinder in position to be assembled; and

Figure 9 is a transverse sectional view on the line 9—9 of Fig. 1.

The hammer as shown comprises a cyl-

inder A having a longitudinal bore for the piston B which reciprocates therein. The forward end of the cylinder is partly closed by a bushing C in which is received the shank of a working tool D, the end of which is adapted to be struck by the reduced projecting head b' of the piston. The rear end of cylinder A is closed by cap E which has screw threaded engagement therewith, the cap having attached thereto or integral therewith the usual grasping handle E' partly shown in Fig. 1. Clamped between the rear end of cylinder A and shoulder e of the cap is the valve housing comprising the valve case F and the valve lid G provided with various ports and passages controlled by a sleeve valve H arranged to reciprocate within the housing. The valve case and lid are locked against movement relative to each other and to the cylinder by dowel pins f on valve case F engaging suitable pin holes f' in the end of the cylinder and by other dowel pins f² engaging cooperating pin holes f³ in valve lid G.

The hammer cylinder is provided with a plurality of longitudinal passages as indicated. The piston return passage 10 (Fig. 1) has a port 10' opening into the outer end of the piston chamber and communicates at its inner end with the longitudinal bore 11 in case F which has a radial exhaust port 11' and an angularly inclined inlet port 11² of restricted size terminating adjacent lid G and registering with an opening g' in the axially projecting annular flange g of the lid which fits within the valve case F. The valve shift passage 12 (Fig. 1) has spaced ports 12' and 12² communicating with the piston chamber adjacent its center and outer end respectively and connects at its inner end with a bore 13 in case F terminating adjacent the forward pressure area 26 of valve H. The hammer cylinder has two exhaust passages 14 (Fig. 2) having ports 14' opening into the piston chamber in the plane of port 12² and communicating with the angularly disposed bores 15 in the valve case which lead directly to the exhaust chamber 16 which communicates with the atmosphere through radial ports 16'. Two live air passages 17 (Fig. 3) in the hammer cylinder have diametrically opposed ports 17' communicating with the piston chamber in the plane of port 12' and at

their inner end communicate with live air passages 18 and 19 in the valve case and valve lid respectively. These passages 17 are filled at all times with live motive fluid 5 from the live air chamber e^2 in the rear of cylinder cap E.

The valve H, which controls the ports and passages, has a forward bearing surface 20 cooperating with the forward bore 21 of case F, a rearwardly disposed bearing surface 22 of greater longitudinal dimensions and slightly greater diameter cooperating with the bore 23 of lid G and an intermediate radially disposed projecting flange 24 cooperating with the enlarged bore 25 of the case F and providing opposed pressure areas 26 and 27 of substantially the same size. The rearward bearing surface 22 of the valve is provided with spaced shallow circumferential grooves 28, one of which is adjacent bearing surface 27 and may serve to make the latter slightly greater in area than surface 26 if desired. Exhaust ports 15' connecting with passages 15 in the case are controlled by surface 20 of the valve, restricted exhaust ports 30 in the case (which communicate with the chamber in the rear of pressure area 27 when the valve is in the forward position shown in Fig. 2) by flange 24, and radial inlet ports 31 in lid H for supplying live motive fluid to the rear of the piston chamber by the rearward bearing surface 22 of the valve.

To provide for access of motive fluid to the rearwardly disposed pressure area 27 of the valve without substantial sacrifice of the cooperating bearing surfaces of the valve and valve housing, a novel construction is utilized, comprising one or more axially disposed recesses or grooves in the bearing surfaces. While these recesses or grooves 32 may be cut in the valve housing, as shown and by preference for reason of convenience and economy in manufacturing they are provided on the valve H in the bearing surface 22 intermediate annular grooves 28 and are two in number (Fig. 7) at diametrically opposite points in order to balance the thrust of the motive fluid on the valve and prevent uneven wear. The motive fluid which thus reaches pressure area 27 of the valve when in its rearward position (Fig. 1) through grooves 32 is bled by restricted leak port 11² with the result that pressure is gradually built up against area 27. By a critical determination of the size of the grooves 32 and port 11² sufficient fluid is admitted to provide for the return stroke of the piston and for the built-up pressure to shift the valve at the proper instant.

The cycle of operation of the hammer is as follows: With the parts in the position shown in Fig. 1, the valve has just been moved to its rearward position through live

air passing from the live air chamber e^2 through passages 19, 18, 17, ports 17', around the reduced neck b^2 of the piston, port 12', shift passage 12, port 13 to the pressure area 26, with the result that the rear of the piston chamber is exhausting through the uncovered exhaust ports 15' in the valve case. Live air is being supplied to pressure area 27 of the valve from chamber e^2 by ports 31, groove 31' and the axial grooves 32 and is thence conducted through restricted port 11², passage 11, return passage 10, port 10' to the front of the piston to drive the latter rearwardly. The size of grooves 32 relative to the restricted or bleed port 11² is such as to provide sufficient built-up pressure against area 27 to cause shifting of the valve in a forward direction soon after the piston B reaches the broken line position of Fig. 1 uncovering exhaust port 14' whereby the pressure behind area 26 of the valve is reduced to the lower pressure obtaining at the front of the piston. The valve then shifts to the position shown in Fig. 2 in time to check the piston by the live motive fluid entering the piston chamber through ports 31 before the piston can strike valve lid G, and at the same time the valve opens both return passage 10 and the chamber behind pressure area 27 to exhaust through ports 30. Pressure of the live motive fluid on the rear end face of the valve holds it in forward position until the reduced neck b^2 of the piston again enters the plane of ports 12' and 17'.

From the above it will be apparent that no area of the valve is continuously subjected to fluid pressure; that the shifting of the valve is effected by alternately subjecting opposed pressure areas thereof to live motive fluid; that the valve is positively held in both positions without any tendency to flutter; that a portion of the pressure applied to one of said areas is utilized for the return stroke of the piston so that this area is subjected to a built-up pressure; that by providing one or more axial grooves in the bearing surface for the valve a greater bearing surface therefor is provided with consequent less wear; that this last named arrangement readily permits a critical determination of the amount of pressure admitted to said area; that the location of live air ports such as the grooves above mentioned at diametrically opposite points balances the thrust upon the body subjected to the pressure with a consequent decrease in wear; and that the arrangement of bearing surfaces in the valve case, lid and valve whereby wear extends to the inner edges of said surfaces in case and lid permits the easy insertion of oversize valves when wear becomes appreciable.

I claim:

1. In a fluid pressure operated tool, in

combination, a cylinder having a piston chamber, a piston reciprocable therein, a valve housing, admission and exhaust ports and passages in said cylinder and housing, a sleeve valve for controlling said ports and passages reciprocable in said housing and adapted to have said piston pass therewithin, a broad bearing surface on said valve adjacent a pressure area thereof, said surface having diametrically opposite axial grooves for admitting motive fluid in restricted amount to said area in one position of said valve, and means uncontrolled by said piston for utilizing a predetermined portion of the motive fluid so admitted to drive said piston in one direction, thus producing a building up of pressure against said area which becomes effective at the proper instant to shift the valve.

2. In a fluid pressure operated tool, in combination, a cylinder having a piston chamber, a piston reciprocable therein, a

valve housing, admission and exhaust ports and passages in said cylinder and housing, an imperforate sleeve valve for controlling said ports and passages reciprocable in said housing and adapted to have said piston pass therewithin, a broad bearing surface on said valve adjacent a pressure area thereof, said surface having diametrically opposite axial grooves for admitting motive fluid in restricted amount to said area in one position of said valve, and means including a bleed port uncontrolled by said piston for conducting away a portion of the motive fluid so admitted to effect rearward movement of said piston, thus producing a building up of pressure against said area which becomes effective at the proper instant to shift the valve.

Signed by me at Detroit Michigan this 40
1st day of June 1923.

EDWARD W. STEVENS.
